UNITED STATES PATENT OFFICE.

RANDOLPH E. SPENCER GEARE, OF CHICAGO, ILLINOIS.

CHAIN GRATE.

Application filed January 10, 1920. Serial No. 350,585.

To all whom it may concern:

Be it known that I, RANDOLPH E. SPENCER GEARE, a citizen of the United States, residing at Chicago, in the county of Cook and State of Illinois, have invented certain new and useful Improvements in Chain Grates, of which the following is a specification.

This invention relates to improvements in chain grates and has for its object to provide 10 a chain grate constructed of readily detachable individual grate bars locked or secured in position upon transverse supporting bars in such wise that bars, which must be replaced, may be readily removed and new 15 ones substituted without interfering with the use of the grate.

These and other objects will be more fully explained and set forth in the following specification and shown in the accompanying 20 drawings in which—

Figure 1 is a plan view of a section of chain grate embodying my invention.

Fig. 2 is a side elevation of the same.

Fig. 3 is an inverted plan view of one of 25 the supporting bars.

Fig. 4 is a section taken along the line 4—4 of Fig. 1.

Fig. 5 is a perspective of the locking key.

Fig. 6 is a fragmentary side elevation of 30 the grate showing the same in its travel over the rear sprocket wheels.

Like numerals refer to like elements throughout the drawings in which 10 indicates generally a transverse supporting bar, 35 a plurality of these bars being provided in a complete mechanism, these bars being secured at each end to a link 11 of drive chains 15, the latter adapted to coact with and ride over sprocket wheels 16. The bars 40 10 are provided with the end portions 10^a adapted to fit between the lugs 11^a projecting from the side of the chain links 11 and being secured thereto by means of a fastening pin, or the like, passed through apertures 11^b 45 in the lugs 11^a and aperture 10^b in the end of the bar 10. The links 21 composing the side drive chains (see Fig. 6) obviously need only be provided with one pair of lugs 11^a, while the links of intermediate chains will 50 have two pairs of lugs 11^a one on each side thereof as shown in Figs. 1 and 2. Each of the bars 10 is provided with a plurality of dovetail grooves or seats 10^c, a key-way being formed in the bottom of each seat, as indicated by numeral 10^d, the bottom of such 55 key-way being inclined slightly adjacent one

side of the supporting bar to form the edge or vertex 10^e.

A plurality of fuel supporting grate bars 13 are provided, each of these grate bars 60 having offset arms 13^a provided with suitable inclined draft passages 13^b in the sides thereof. These arms extend in opposite directions from the central portion 13^c, the latter being provided with a tongue 13^d on 65 the under side thereof adapted to fit in the dovetail grooves or seats 10^c of the supporting bar 10, as shown in Figs. 2 and 4, for example.

A locking key 14 is provided to lock each 70 of the grate bars in position, as shown on Fig. 4, these keys being each provided with a pair of upwardly projecting lugs 14^a, 14^b and a pair of downwardly projecting lugs 14^c, 14^d, see Fig. 5. In assembling the grate 75 bars, the keys 14 are first placed in the keyways 10^d and allowed to tilt over the edge 10^e to permit partial insertion of the tongue 13^d of the grate bar which may then be driven home by a sharp blow into its dovetail seat 80 10^c, the key 14 being constructed of resilient metal, such as spring steel, and bending or tilting sufficiently about the edge 10^e to permit the passage of the tongue 13^d over the lug 14^b, which will thereafter spring into 85 normal position shown in Fig. 4 in which position the lugs 14^a, 14^b will engage the ends of the tongue 13^d while the lugs 14^c and 14^d will engage the sides of the supporting bar 10 thereby locking the grate bars in position. 90

Should a grate bar become broken or its replacement become necessary for any other reason, the same may be removed and replaced during its passage over one of the sprocket wheels of the mechanism, the separation of the grate bars at this point (see Fig. 6) in the travel of the grate being sufficient to permit of the insertion of a cold chisel or the like between the arms 13^a of said bars so that the end of the key 14, preferably the end 14^b, may be broken off or bent downwardly permitting quick removal of the bar. A new grate bar may then be readily replaced with a new key in the manner described above. I find that this operation may be readily accomplished while the stoker is in operation, the rate of travel thereof being sufficiently slow to permit this replacement. 100

It will be apparent that my invention is 110 susceptible of numerous modifications and improvements and I do not wish to be re-

stricted to the form shown except as defined in the appended claims.

What I claim is:—

1. In a traveling grate, parallel transverse supporting members, grate bars carried thereby, each of said bars being provided with a central portion and relatively offset arms, said central portion of each bar having a dovetail connection with its supporting member, the arms of one transverse set of bars extending between the spaced apart arms of the transverse set of bars on either side thereof, and individual key members to hold said bars in position on said transverse members, said key members being so located and arranged as to project on either side of said central portions of said bars in such wise as to be accessible when the preceding transverse set of bars in direction of movement is inclined.
2. In mechanism of the class described, a grate bar, a supporting member therefor having a seat therein and a key-way, the bottom of said key-way being inclined to provide an edge intermediate its extremities, and a key fitting in said key-way and having a portion engageable with said bar when the latter is seated in said seat, said key being constructed and arranged to yieldingly bend over said edge when said bar is being moved to seating position and thereafter spring to position with said engageable portion engaging said bar.
3. In a traveling grate, a supporting bar having a plurality of transverse seats therein, grate bars adapted to fit said seats, and individual spring means for retaining said grate bars in seated position.
4. In a traveling grate, a supporting bar having a plurality of transverse seats there-

in, grate bars adapted to fit said seats, and individual means for retaining said grate bars in seated position, said means being resilient and adapted to spring into operative position as said grate bars are seated.

5. In mechanism of the class described, a supporting member having a seat and a key-way, a grate bar seated in said seat, and a spring key seated in said key-way and securing said bar in seated position, said key having a shoulder at one end engaging said bar and a shoulder at its other end engaging said supporting member.

6. In mechanism of the class described, a supporting member, said supporting member having a seat, a grate bar having a portion engageable with said seat, and spring means to lock said bar in seated position.

7. In mechanism of the class described, a grate bar, a supporting member therefor having a seat therein and a key-way, the bottom of said key-way being inclined to provide an edge intermediate its extremities, and a key fitting in said key-way and having a down-turned portion at one end adapted to engage one side of said supporting member and an up-turned portion at its other end adapted to engage said grate bar when the latter is seated in said seat, said key being constructed and arranged to yieldingly bend over said edge when said bar is being moved into seating position and to thereafter spring into position with its end portions engaging said supporting member and said bar, respectively.

In testimony whereof, I have subscribed my name.

R. E. SPENCER GEARE.
